UNITED STATES PATENT OFFICE.

RALPH V. L. HARTLEY, OF SOUTH ORANGE, NEW JERSEY, ASSIGNOR TO WESTERN ELECTRIC COMPANY, INCORPORATED, OF NEW YORK, N. Y., A CORPORATION OF NEW YORK.

ELECTRON TUBE.

Application filed September 2, 1924. Serial No. 735,263.

This invention relates to wave transmission, and more particularly to the conversion of mechanical waves into electrical waves.

Objects of the invention are to efficiently convert mechanical waves, for example, speech or sound waves, into electrical waves without substantial distortion; to transmit mechanical waves without substantial distortion through the wall of a sealed chamber; and to selectively transmit mechanical waves to a movable control element in a space current device thereby to vary the impedance of the device.

These and other objects of the invention are attained in a space current device having a mechanical frequency selecting system arranged to selectively transmit mechanical waves through a flexible portion of the wall of the device, the mechanical waves causing the size of the apertures in the grid or space current control element of the device to vary, thereby to produce space current waves corresponding to the mechanical waves. The mechanical waves may be induced by speech or other sound waves impinging on an acoustic diaphragm coupled with the filter.

In the accompanying drawing, Fig. 1 is a diagrammatic view, partly in section, of a space current device constructed in accordance with the invention, Fig. 2 is a fragmental view of a modification of Fig. 1 between dotted lines X and Y, and Fig. 3 is a plan of one of the grids in Fig. 2.

Referring to Fig. 1, the evacuated sealed chamber 10, having walls of glass, or other suitable insulating material, is provided with two oppositely disposed axially aligned tubes 11 and 12 which may be of metal, or other suitable material, sealed to the glass 10. Tube 11 is sealed at its outer end by the flexible diaphragm 13, tube 12 being similarly sealed at its outer end by flexible diaphragm 14. Chamber 10 encloses a filamentary cathode 15, the coaxial cylindrical anode 16, and helical spring grid 17 interposed coaxially between cathode 15 and anode 16. Cathode 15 is heated by a source of current 18 to cause the emission of electrons or space current. The source of space current 19 is connected in the usual manner between cathode 15 and anode 16, the space current passing through the primary winding of output transformer 20, which provides an output circuit for the device.

A mechanical frequency selecting system 55 or wave transmission filter 21, supported in tube 11, is made up of a plurality of masses 22 supported in spaced relation from each other within tube 11 and coupled together in series with each other and with diaphragm 60 13 by means of the elastic elements or springs 23. Each of the masses 22 is, or may be, concentrated and supported near the center of a separate diaphragm or other suitable supporting element 24, mounted in tube 11. 65 Diaphragms 24 are spaced apart in substantially parallel relation, and may entirely, or only partially, close the opening through tube 11. Preferably, supports 24 have very small or negligible stiffness, while springs 23 70 preferably have very small or negligible masses. The left hand end of grid 17 is attached, preferably by means of electrical insulation 17', to mass 22 at the right hand terminal of filter 21, while the right hand end of grid 17 is similarly attached to mass 22 at the left hand terminal of filter 25.

Filter 25 is of similar construction to filter 21 and is supported in tube 12 in a manner similar to that described in connection with filter 21 and tube 11. The masses of diaphragms 13 and 14 function similarly to the concentrated masses 22. Diaphragm 14 is coupled by means of spring 26 to the mechanical resistance 27 of any well known 80 form, being illustrated as a plunger 28 subjected to the viscous or frictional action of the comminuted material 29 in container 30.

Filters 21 and 25 may be treated analytically similarly to electric wave filters. Masses 90 22 and the masses of diaphragms 13 and 14 correspond to inductance elements in series with an electrical line. Diaphragms 13 and 14 by virtue of their stiffness correspond to capacity elements connected in series with the inductances corresponding to these diaphragms. Springs 23, 17 and 26 correspond to shunt capacity elements. Mechanical resistance 27 provides a simple form of terminating impedance requisite for a uniform response over the frequency range of transmission of the filter. When the space current device is to be employed as a telephone transmitter, diaphragm 13 may be employed as an acoustical diaphragm.

For the purpose of transmitting, without substantial distortion, speech or other sound waves within a useful frequency range, fil-

ters 21 and 25 may be designed to efficiently transmit, without serious attenuation, all waves having frequencies lying within a range having predetermined limits, while waves of all frequencies lying outside this range are greatly attenuated or substantially extinguished. The design of such a filter may be readily accomplished by reference to well known data employed in the computation of the constants of electric wave filters, use being made of the relation, explained above, between the constants of an electric filter and of a mechanical filter. A typical form of electrical filter, corresponding to mechanical filters 21 and 25, is shown in Fig. 7 of G. A. Campbell Patent 1,127,113, dated May 22, 1917, and the method of designing such a filter is explained in the patent.

In order to withstand the pressure of the atmosphere, diaphragms 13 and 14 are comparatively stiff. The amplitude of the motion of these diaphragms is, therefore, small, and the motion of grid 17 is accordingly small. In order to increase the deflection of grid 17, filters 21 and 25 may be tapered, that is, the constants of successive sections of the filters may converge in value. It has been found that by selecting proper values for such a tapered filter a suitable deflection may be produced in grid 17. The filter may have any number of recurrent sections 22, 23 required to produce the desired transmission characteristic.

In a specific example, a seven-section filter capable of transmitting without distortion wave frequencies lying between 200 cycles and 2500 cycles per second contains elements having the constants given below, the values in the first column representing the masses in successive sections of the filter 21 starting with diaphragm 13 and going to the right, while the values given in the other column represent the reciprocals of the elasticities of springs 23. Diaphragms 13 and 14 each have a mechanical resistance of 1000 dynes, the mechanical resistance being a measure of the force required to impart a velocity of one centimeter per second to the diaphragm. The mass 22 in each filter 21 and 25, nearest to grid 17, has a mechanical resistance of 100 dynes.

65 In this instance, diaphragms 13 and 14 each

have a mass of such value that it may be considered concentrated at the center of the diaphragm as a mass of .664 grams, the filters 21 and 22 being made up of sections which contain successively smaller masses 22 as they approach grid 17.

In the operation of the space current device sound waves lying between the frequency limits of transmission of filter 21 are transmitted from diaphragm 13 through filter 21, grid 17 and filter 25 to resistance 27, this resistance preventing reflection of the transmitted wave back through the filter. Owing to the relative movements of opposite ends of the elastic helical grid 17, the apertures between adjacent turns of the grid vary in size and produce corresponding fluctuations in the space current through the device, the resulting wave being transmitted to output transformer 20. The electric wave thus produced corresponds closely to the mechanical or acoustic wave impressed upon diaphragm 13, and the amplitude of the electrical wave is enhanced by the amplifying action of the three element space current device.

Instead of sealing tubes 11 and 12 by diaphragms 13 and 14 at the outermost ends of the tubes, any one of the supports 24 may be employed as a sealing diaphragm, and if this is done, it is preferable to arrange a tapered filter on each side of the sealing diaphragm in order to avoid a sharp discontinuity in the transmission characteristic of the filter at this diaphragm.

In Fig. 2, chamber 10 contains the cathode 15, the anode 31 and the two grid elements 32 and 33 interposed between the cathode and anode. Grid 32 is rigidly coupled to mass 22 of filter 21, preferably by electrical insulation. Grid 33 is elastically coupled at one end to grid 32 by means of spring 34, and rigidly coupled at its other end to mass 22 of filter 25, grid 33 being preferably insulated from filter 25. Each of the grids 32 and 33 is provided with the parallel apertures 36 as shown in Fig. 3, which are disposed transversely to the direction of movement of the grids, the movement being produced by deflection of diaphragms 24 and spring 34. The apertures 36 in the two grids register with each other in such a manner that motion of grid 32 with respect to grid 33 varies the effective size of the effective apertures through the grid as a whole between cathode 15 and anode 21. Grids 32 and 33 are held parallel to each other by the stiffness and configuration of their supports.

When grid 32 vibrates longitudinally, that is, from left to right and vice versa, in the figure, in response to mechanical waves from filter 21, grid 33 moves relatively thereto and in a parallel direction in accordance with the wave motion transmitted thereto,

thus producing shifts between grids 32 and 33 and corresponding variations in the effective size of the apertures presented by them. The resulting variations in the impedance of the space current device produce electrical waves corresponding to the mechanical waves.

It will be noted that grid 17, Fig. 1, and grid 31, 32, Fig. 2, are so coupled to filters 10 21 and 25 that any one aperture in the grid (a pair of registering apertures comprising, in effect, a single aperture in the case of grid 17, Fig. 2), may be looked upon as having two sides elastically coupled together, one side being coupled to one filter and the other side to the other filter. When 15 a wave is transmitted from one filter to the other through the elastic coupling between the sides of the aperture the deflection of this coupling produces corresponding variation 20 in the size of the aperture and similar variations in the impedance of or the space current through the device.

While the invention has been described 25 with specific reference to certain species illustrative of the invention, it is to be understood that the invention may be carried out in various ways and be embodied in various forms as defined in the appended 30 claims.

What is claimed is:

1. In a space current device, a movable space current control element, and a tapered mechanical wave transmission filter coupled therewith.
2. In a space current device, a movable space current control element, a vibratory diaphragm, and a tapered wave filter connected between said diaphragm and said control element.
3. In a space discharge device, a space discharge path, a control electrode adapted to vary the discharge by its motion, an enclosing vessel, and means for transmitting wave motion to said electrode, said means comprising a tapered wave filter having its stiff end connected to the wall of said vessel and its flexible end connected to said electrode.
4. In a space discharge device, a discharge path, a control electrode, an enclosing vessel, and a mechanical coupling system connected to said electrode and to the wall of said vessel, said coupling system comprising a broad band wave filter adapted to transform the wave motion, whereby a small motion impressed upon the wall of the enclosing vessel is converted to a proportionately increased motion of said electrode.
5. In a space discharge device, a discharge controlling electrode, an enclosing vessel, and a mechanical coupling system adapted to transfer motion from the walls of said vessel to said electrode, said coupling system comprising a doubly tapered filter having end

sections of high impedance and middle sections of low impedance, said end sections being connected to portions of the walls of said vessel and said control electrode being connected to a point in a middle section.

6. In a space current device, a longitudinally extensible grid having transverse apertures therein, and a mechanical frequency selecting system coupled to one end of said grid.

7. In a space current device, a longitudinally extensible grid having transverse apertures therein, and a separate mechanical frequency selecting system coupled respectively to each end of said grid.

8. In combination, a vessel having a flexible portion, a movable element within said vessel, and a mechanical frequency selecting system connected to said movable element and to said flexible portion, said system having recurrent sections.

9. In combination, a vessel having a plurality of flexible portions, an element within said vessel having relatively movable parts, and a plurality of mechanical frequency selecting systems, each of said flexible portions being connected by a single one of said frequency selecting systems to a separate one of said movable parts.

10. In a space current device, a grid having an aperture, the opposite sides of which are elastically coupled together, a mechanical frequency selecting system coupled to one side of said aperture, and another mechanical frequency selecting system coupled to the other side of said aperture.

11. In a space current device, a control element having at least a portion which is movable, and a mechanical frequency selecting system coupled to said movable portion, said system including a plurality of springs of predetermined elasticity, and a plurality of predetermined masses coupled together in series by said springs.

12. In a space current device, a control element having at least a portion which is movable, and a mechanical frequency selecting system coupled to said movable portion, said system including a plurality of springs of predetermined elasticity, a plurality of predetermined masses coupled together by said springs, and means for supporting said masses in position.

13. In a space current device, a control element having at least a portion which is movable, a mechanical frequency selecting system coupled to said movable portion, said system including a plurality of springs of predetermined elasticity, a plurality of predetermined masses coupled together by said springs, and a separate diaphragm supporting each of said masses.

14. In a space current device, a control element having two portions which are movable with respect to each other, and a sep-

- arate mechanical frequency selecting system coupled to each of said portions, each of said systems having recurrent sections.
15. In a space current device, a control element having at least a portion which is movable, a mechanical frequency selecting system coupled to said movable portion, said system having recurrent sections, and a mechanical resistance coupled to one of 10 said sections.
16. In a telephone transmitter, a space current device having an anode, a cathode and a control element, means whereby a space current is produced between said anode and 15 cathode, said control element having at least a portion which is movable for varying the impedance of said device, a mechanical frequency selecting system coupled to said movable portion for transmitting mechanical 20 waves thereto, and an output circuit associated with said device for receiving the resulting electrical waves.
17. In a space current device, a vessel containing a control element having at least a 25 portion which is movable, a tube extending from one side of said vessel, and a mechanical frequency selecting system housed in said tube and coupled to the movable portion of said control element.
30. 18. In a space current device, a vessel containing a control element having two portions movable with respect to each other, a pair of tubes separately extending from said vessel, and a separate mechanical frequency 35 selecting system housed in each said tube and coupled respectively to the movable portions of said control element.
19. In a space current device, a vessel containing a control element having two por-
- tions movable with respect to each other, a pair of axially aligned tubes extending respectively from opposite sides of said vessel, and a mechanical frequency selecting system housed in each said tube and coupled respectively to the movable portions of said control element.
20. In wave transmission apparatus, a vessel containing an element having at least a portion which is movable, and a mechanical frequency selecting system coupled to the movable portion of said element, said system including a diaphragm forming a portion of the wall of said vessel.
21. In wave transmission apparatus, a vessel containing an element having at least a portion which is movable, and a mechanical frequency selecting system coupled to the movable portion of said element, said system including a plurality of spaced diaphragms supported by said vessel, one of said diaphragms forming a portion of the wall of said vessel, each of said other diaphragms having a mass concentrated near its center, and elastic couplings between said masses.
22. In a space current device, a grid having an aperture the opposite sides of which are elastically coupled together, a mechanical frequency selective system coupled to one side of said aperture, another mechanical frequency selecting system coupled to the other side of said aperture, and a mechanical resistance coupled to said other mechanical frequency system.

In witness whereof, I hereunto subscribe my name this 26th day of August, A. D. 75 1924.

RALPH V. L. HARTLEY.
